(57) **CLAIM**

The ornamental design for a bicycle auxiliary handle joint, as shown and described.

DESCRIPTION

FIG. 1 is a front elevational view of a bicycle auxiliary handle joint showing our design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof; and,

FIG. 8 is a perspective view of the bicycle auxiliary handle joint on a reduced scale, shown in position of use on an auxiliary handle, connecting a handlebar and the auxiliary handle, which are shown in broken lines for illustrative purposes only and form no part of the claimed design.
